UNITED STATES PATENT OFFICE

2,511,570

LIFT MECHANISM FOR SLIDING DOORS

Frank Ditchfield, Cleveland, Ohio, assignor to The Youngstown Steel Door Company, Cleveland, Ohio, a corporation of Ohio

Application April 5, 1947, Serial No. 739,586

3 Claims. (Cl. 16—99)

1

This invention relates to lift mechanism for sliding doors of railway house cars.

It is an object of this invention to provide lift mechanism for sliding doors of railway house cars so constructed and disposed as to materially reduce the over-all distance between mechanisms on opposite sides of the cars and permit a substantial increase in the inside width of such cars.

A further object is to provide lift mechanism of the character set forth above which shall permit an increase in the inside width of railway house cars without modification of the body of said cars.

A further object is to provide lift mechanism for sliding car doors which shall embody interchangeable roller retainers that do not require normally superfluous material to obtain interchangeability.

A further object is to provide lift mechanism for sliding doors which shall permit elimination of lever guide brackets heretofore utilized with such mechanism.

A further object is to provide lift mechanism for sliding doors so constructed and arranged that bars connecting the roller retainers of said mechanism for simultaneous operation shall be subjected to tension rather than compression upon operation of said mechanism.

A further object is to provide lift mechanism for sliding doors which shall embody operating levers capable of disposition on the outside of and wholly within the outer plane of the doors.

A further object is to provide lift mechanism for sliding doors which shall obtain a reduction in cost.

A further object is to provide lift mechanism for sliding doors whose projection outwardly from the doors shall be so restricted as to obtain a single standard mechanism suitable for use upon cars of varying widths without exceeding the prescribed minimum limits.

Other objects of the invention will become clear as the description thereof proceeds.

In the drawings forming part of this specification:

Fig. 1 is a fragmentary elevation showing a lift mechanism embodying the instant invention applied to a sliding railway house car door, the door being shown in lowered position.

Fig. 2 is a view similar to Fig. 1, the door being shown in elevated position.

Fig. 3 is a horizontal section taken on line 3—3 of Fig. 1.

Fig. 4 is an end view of the rear edge of the door.

2

A preferred embodiment of the instant invention is shown applied to one type of sliding railway house car doors. The door 10 utilized for the purpose of illustrating the invention embodies a construction more clearly illustrated and described in the co-pending application of Wilfred A. Beauchamp, Serial No. 640,767, filed January 12, 1946. As illustrated, the door 10 embodies a corrugated metallic panel 11 whose front, rear, and bottom marginal portions are inclined outwardly as indicated at 12, 13 and 14 from the main or inner plane of the panel and terminate in flanges 15, 16 and 17 parallel to the panel and lying in the outer plane thereof.

15 The lower margin of the panel is reinforced by means of a backing plate 18 secured to the inner face of the panel 11 substantially in the main plane thereof as by means of rivets 19. The lower margin of the panel is also reinforced by 20 means of a plate 20 secured as by means of rivets 21 to the outwardly offset margin 17 of the panel. Below the lower edge of the panel 11 plate 20 is inclined downwardly and outwardly as indicated at 22 beyond the outer plane of the panel. 25 Plate 20 then extends downwardly as indicated at 23 inwardly as indicated at 24 and terminates in a relatively short upstanding flange 25 which is secured preferably by welding to the outer face of the backing plate 18.

30 The front vertical margin of the door is reinforced by means of a substantially Z-shaped member having a flange 26 secured upon the flange 15 and the bottom plate member 20, an inwardly extending web 27, a forwardly extending flange 28, and an outwardly extending flange 29. To obtain securement of the flange 26 of the front vertical reinforcement upon the bottom plate member 20 the latter is offset inwardly as indicated at 30.

35 40 The rear vertical margin of the door is reinforced by means of a substantially W-shaped member having a flange 31 secured upon the flange 16 of the panel and the bottom plate member 20, an inwardly extending web 32, a rearwardly extending flange 33 and an inwardly extending flange 34. In order to obtain securement of the flange 31 of the rear vertical reinforcement upon the bottom plate 20, the latter is offset inwardly as indicated at 35.

45 50 From the foregoing description it will be apparent that the door panel 11, backing plate 18, bottom plate 20, and the front and rear vertical reinforcing members constitute a substantially tubular formation within which the lift mechanism of the instant invention is adapted to be re-

ceived. This mechanism embodies identical and interchangeable roller retainers 36 and 37 carrying pins 38 and 39 upon which rollers 40 and 41 are mounted. The front roller retainer 36, which is preferably in the form of a casting, is provided with outer and inner trunnions 42 and 43 disposed in offset relationship to the roller pin 38 and journalled respectively in the bottom plate 20 and in the web 44 of a substantially bathtub-shaped bracket 45 secured as by means of rivets 46 and 47 to the bottom plate 20. Similarly, the rear roller retainer 37 carries outer and inner trunnions 48 and 49 which are offset relatively to the roller pin 39 and are journalled respectively in the bottom plate 20 and in the web 50 of a substantially bathtub-shaped bracket 51 which is secured as by means of rivets 52 and 53 to the bottom plate. It will be apparent from Figs. 1 and 3 of the drawings that although the roller retainers 36 and 37 are fully interchangeable, this is accomplished without the use of any superfluous material as has heretofore been required.

Simultaneous operation of the roller retainers 36 and 37 is obtained by means of a connecting bar 54 the ends of which are mounted upon pins 55 and 56 fastened respectively to the roller retainers. In view of the fact that the connecting bar 54 is placed in tension upon the operation of the lift mechanism as hereinafter more fully explained, this bar may be in the form of a flat strap or any other member to which tension only may be applied.

In order to actuate the roller retainers to impart lift to the door, a lever and a link are employed. The lever 57 is pivotally mounted at its lower end upon the rearwardly extending flange 33 of the rear vertical reinforcing member. For this purpose a plate 58 is secured as by means of rivets 59 upon the inwardly offset portion 60 of the bottom plate 20. The plate 58 extends rearwardly in spaced overlapping relationship with the flange 33. The lower end of the lever 57 lies within this space and is secured to the plate member 58 and the flange 33 as by means of a rivet 61 which carries a sleeve S adapted to maintain the lever against shifting along the rivet. It will be apparent particularly from Fig. 3 of the drawings that the plate member 58 lies inwardly of the outer plane of the door and that while the lever 57 lies upon the outside of the door, it too is within the outer plane of the door.

A link 62 is pivotally mounted upon the pin 56 of the rear roller retainer 37 and is pivotally connected to the lever 57. For this purpose a substantially Z-shaped plate 63 is secured upon the inner face of the lever 57 as by means of rivets 64 so that the link 62 may be received between the plate 63 and the lever and pivotally fastened thereto as by means of a rivet 65. To permit the pivotal connections between link 62 and the lever 57, the web 32 of the rear vertical reinforcing member is slotted as indicated at 66. The pivotal connection between the link 62 and the lever 57 is not only obtained in this manner but the slot 66 serves additionally as a guide and retaining means for the link and the lever thereby eliminating the guide and retaining quadrants normally utilized in connection with the operating levers of other lift mechanisms.

It will be apparent from the foregoing that the entire lift mechanism lies wholly within the outermost plane of the door. To move the door from the closed position illustrated in Fig. 1 of the drawings the operating lever 57 is pulled

downwardly in clockwise direction as shown in Fig. 2 of the drawings. A corresponding pull is exerted through the link 62 upon the rear roller retainer 37. This retainer in turn exerts a pull upon the connecting bar 54 which imparts simultaneous movement to the front roller retainer 36. The door is thereby lifted uniformly above the supporting track 67 through the pivotal engagement between the trunnions on the roller retainers and their bearings in the brackets 45 and 51 and bottom plate 20. When the door has been elevated, its weight has been transferred from the track directly to the rollers and it may then readily be moved in opening direction. Upon the release of the operating lever 57 the door will automatically re-seat itself upon the track. When the door is thus frictionally supported upon the track the roller retainers 36 and 37 are caused to bear against resilient rubber blocks 68 and 69 whereby the vertical position of the operating lever 57 is maintained.

It will be apparent that numerous changes and modifications in the details of the invention will be clear to those skilled in the art. It is intended, therefore, that all such modifications and changes be comprehended within this invention which is to be limited only by the scope of the claims appended hereto.

I claim:

1. In a railway house car having a sliding lift door embodying a panel, covering means on the lower margin of said door extending outwardly of the inner plane of said panel and lying within the tunnel clearance limit of said car, the rear margin of said door lying inwardly of said covering means, spaced front and rear roller retainers disposed within said covering means and outwardly of the inner plane of said panel, means operatively connecting said retainers in lifting relationship with said door, rollers carried by said retainers, means within said covering means connecting said retainers for simultaneous movement, a vertical lever pivotally mounted upon said rear margin and on the outside of said door, said lever lying inwardly of said covering means, a link within said covering means pivotally connected to said rear retainer, a slot in said door, between said panel and said covering means, said link extending through said slot and being pivotally connected to said lever, the operation of said lever to elevate said door placing said connecting means and link in tension.

2. In a railway house car having an outside sliding lift door, said door having a box section along the lower margin thereof terminating short of the rear edge of said door to provide a marginal portion lying inwardly of the outer plane of said box section, the outer plane of said box section lying within the tunnel clearance limit of said car, door lifting means within said box section, a vertical lever pivotally mounted on said marginal door portion inwardly of the outer plane of said box section, a link pivotally connected to said lifting means, said link extending through a slot in said door, and means pivotally connecting said link to said lever.

3. In a railway house car having an outside sliding lift door, said door having a box section along the lower margin thereof embodying an outer plate member lying within the tunnel clearance limit of said car and terminating short of the rear edge of said door and rear vertical reinforcing member, said reinforcing member having a forwardly extending flange overlapping said plate member, a flange extending inwardly therefrom

across said box section, and a rearwardly extending flange lying inwardly of said plate member, door lifting means within said box section, a vertical lever pivotally mounted on said last mentioned flange in each of said plate members, a link pivotally connected to said lifting means, said link extending through a slot in said inwardly extending flange, and means pivotally connecting said link to said lever.

FRANK DITCHFIELD.
